STRAINER

Thomas Wheatley, Houston, Tex.

Application December 8, 1938, Serial No. 244,511

3 Claims. (Cl. 210—164)

This invention relates to a strainer.

An object of the invention is to provide a strainer of the character described designed to be incorporated into a fluid conducting line, such, for example, as a pipe line, for collecting solid particles, objects and detritus that may be in the liquid being conducted.

Another object of the invention is to provide a casing adapted to be connected into a line, a strainer mounted therein and readily removable therefrom which will collect solid particles and matter from the liquid flowing through the line and which may be readily removed at intervals for cleansing and unclogging the strainer.

A further object of the invention is to provide a strainer embodying a novel type of skeleton or framework with foraminated screening material thereon, all of special formation to be seated and secured in a strainer casing designed to be incorporated into a fluid conducting line.

With the above and other objects in view, the invention has particular relation to certain novel features of construction, arrangement of parts and use, an example of which is given in this specification and illustrated in the accompanying drawings, wherein:

Figure 1 shows a perspective sectional view.

Figure 2 shows a transverse sectional view taken on the line 2—2 of Figure 1, and

Figure 3 shows a transverse sectional view of the strainer, apart from the casing.

Referring now more particularly to the drawings, wherein like numerals of reference designate the same parts in each of the figures, the numeral 1 designates a strainer casing having the tubular end connections 2, 3 formed for the connection of adjacent sections of a flow line thereto. As shown the connections 2, 3 have the external annular flanges 4, 5 for forming said connections with the adjacent sections of the line.

The casing 1 has the external, approximately rectangular top flange 6 and has a removable cover plate 7, the margins of the cover plate and top flange being provided with registering notches 8, 9 to receive the securing bolts 10. The lower ends of these bolts have the heads 11 engageable with the under side of the flange 6 and the clamp nuts 12 which are threaded on the upper ends of the bolts to clamp the cover plate in place. The cover plate forms a close fitting joint 13 with the top of the casing whereby to prevent leakage.

Within the casing 1 there is a basket-like strainer which is composed of the perforated end plates 14, 15 connected by the perforated anchor

bars 16, 16 which are arcuate in cross section as is more accurately shown in Figure 2. The end plates and anchor bars are formed of any selected material and form a rigid skeleton, or framework. The up-stream end plate 14 is provided with an inlet opening 17 which registers with the passageway through the inlet end connections 2. The top, bottom and side walls of the strainer are formed of suitable foraminated material such as durable wire mesh, whose ends are anchored to the corresponding margins of the end plates 14, 15 and at the bottom this material fits closely within the anchor bars 16, 16, and is supported thereby.

As will be noted, the end plate 14 fits closely against the up-stream end of the casing 1, around the inlet opening and the strainer is supported on suitable bottom supports 19 in the casing and is maintained in spaced relation with the side 10 walls of the casing by the inside spacers 20 as more accurately shown in Figure 2. The end plate 15 is spaced from the downstream or outlet passageway of the casing so as to not block or restrict said outlet casing, and abuts the spaces 24, extending inwardly from the opposing end 25 of the casing.

Upstanding from the end plates 14, 15 are the grips or handles 21, 21, against which the cover 7 abuts when in closed position.

The liquid flowing through the line will enter the strainer as indicated by the arrows in Figure 1 and will be forced to pass out through the screening material 18 and can pass also through the perforated end plates into the space around 30 the strainer from which it may pass on through the outlet.

All solid particles carried by the liquid will be entrapped within the strainer and can thus not reach nor interfere with the operation of the 35 pumps.

From time to time the strainer should be removed for cleansing and this may be easily accomplished by removing the bolts 10 and opening the cover plate 7 so that the strainer may be 40 readily lifted out, cleansed and replaced.

The casing 1 is provided with a drain opening 22, normally closed by a plug 23 and through which solid material collecting in the bottom of the casing may be removed.

The drawings and description disclose what is now considered to be a preferred form of the invention, by way of illustration only, while the broad principle of the invention will be defined by the appended claims.

What I claim is:

1. A strainer assembly comprising a casing having an inlet and an outlet in alignment with the inlet, a removable cover on the casing and forming a fluid tight joint therewith, a strainer in the casing comprising end plates, anchor bars connecting the end plates, said strainer having a foraminated top, bottom, and sides and whose margins are secured to the end plates, the upstream end plate having an opening which registers with said inlet, grips upstanding from the strainer and abutting the cover.

2. A strainer assembly comprising a casing having an inlet and an outlet in alignment with the inlet, a removable cover on the casing and forming a fluid tight joint therewith, a strainer in the casing comprising foraminated end plates, anchor bars connecting the end plates, said strainer having a foraminated top, bottom, and sides and whose margins are secured to the end plates, the upstream end plate having an opening which registers with said inlet, and means for spacing the strainer from the casing walls.

3. A strainer assembly for liquid conducting

lines comprising a casing having an inlet opening and an outlet opening in alignment with the inlet opening, a removable cover for the casing which is parallel to the axis of the openings, a removable strainer in the casing having perforated end plates, anchor bars connecting the end plates, a top, bottom and side walls for the strainer formed of foraminated material, the bottom of the strainer being located an appreciable distance beneath the lower side of said openings and the upstream end plate having an opening in registration with the inlet opening, spacing means in the casing abutting the downstream end of the strainer and maintaining said downstream end spaced from the downstream end of the casing and maintaining the upstream end of the strainer in close contact with the corresponding upstream end of the casing, upstanding bottom supports in the casing supporting the strainer spaced from the bottom of the casing and inside spacers spacing the strainer from the sides of the casing.

THOMAS WHEATLEY.
